F. GRINHAM.

VALVE SILENCER.

APPLICATION FILED JUNE 24, 1921.

1,390,529.

Patented Sept. 13, 1921.

Inventor:
Frederick Grinham,
By Hugh N. Wagner,
Attorney.

UNITED STATES PATENT OFFICE.

FREDERICK GRINHAM, OF ST. LOUIS, MISSOURI, ASSIGNOR OF ONE-FOURTH TO HENRY W. SPALDING, ONE-FOURTH TO JOHN C. STILES, AND ONE-FOURTH TO GEORGE P. WARD, ALL OF ST. LOUIS, MISSOURI.

VALVE-SILENCER.

1,390,529.

Specification of Letters Patent. Patented Sept. 13, 1921.

Application filed June 24, 1921. Serial No. 480,040.

To all whom it may concern:

Be it known that I, FREDERICK GRINHAM, a citizen of the United States, residing at the city of St. Louis, in the State of Missouri, have invented certain new and useful Improvements in Valve-Silencers, of which the following is a specification.

Any kind of noise in a motor vehicle is objectionable, and it is not only undesirable because of its effect upon the driver and passengers in the way of producing the disagreeable impression of imperfection but, also, is a symptom of wear. One of the things that automobile drivers and others operating similar motors most constantly seek to eliminate is "rattle" of any kind. This invention is a valve silencer for certain types of engines.

In the accompanying drawings forming part of this specification, in which like numbers of reference denote like parts wherever they occur,

Figure 1 is a perspective view of this device;

Fig. 2 is a top plan view showing the same in position and taken on the line 2—2 in Fig. 3, looking in the direction indicated by the arrows;

Fig. 3 is a vertical sectional view through the engine-block and showing this device in position; and

Fig. 4 is a front elevational view taken at a right-angle to Fig. 3.

The valve-silencer 1 may be made of any suitable material but may be preferably made of fiberboard, as the same possesses noise-deadening qualities that other materials lack, especially when considered in conjunction with cheapness, lightness, flexibility, and durability.

The device 1 is, as shown in Fig. 1, substantially elliptical in shape and contains a central slot 2, also substantially elliptical in form.

The specific noise intended to be obviated by this device is the knock or rattle of the lifter-lock 3 against the engine-block 4. To accomplish this the silencer 1 is bent in the shape best seen in Fig. 3, in which the push-rod 5 passes through that part of slot 2 in silencer 1 that occupies a horizontal plane where the ends of silencer 1 have been bent to substantially a right-angle with the main-body part thereof. In this position the long

side-members of silencer 1 rest against engine-block 4 and lie between the same and the lifter-lock 3 like a buffer or gasket, while the lower end part of silencer 1 is interposed between the lower part of lifter-lock 3 and the shoulder 6 of engine-block 4 on which lifter-lock 3 normally abuts and rattles, and thus all rattle of lifter-lock 3 against adjacent parts is prevented.

The silencer 1 must not be creased, for it will break.

In order to place the silencer 1 in working position certain mechanical adjustments are necessary, but with the foregoing explanation of the ultimate location and position and function of the silencer 1 a mechanic skilled with such engine constructions will readily see what parts must be taken out or loosened and replaced.

The installation of this device will stop valve-tappet noise and prolongs the life of tappet-locks and saves the expense of re-fitting and replacing tappet-locks. It keeps the valve-lifter from twisting and turning, thereby making it ride squarely on the valve-lifter cams, and prevents extra wear on valve-lifter cams and lifter.

The elliptical silencer-member 1 may be of any desired size or dimension, but is preferably of about the thickness of thick paper or thin fiberboard and somewhat more than two inches in length. Naturally it will be made of such length and width and thickness as will best suit the particular location for which it is intended. It can be stamped out in quantities.

Having thus described this invention, I hereby reserve the benefit of all changes in form, arrangement, order, or use of parts, as it is evident that many minor changes may be made therein without departing from the spirit of this invention or the scope of the following claims.

I claim:

1. A valve silencer comprising a piece of non-metallic substance having a hole in its center, the same being elongated in its longitudinal dimension, and adapted to serve as a buffer on two surfaces of a movable-member.

2. A valve silencer comprising a piece of non-metallic substance having a hole in its center, the same being elongated in its longitudinal dimension and adapted to serve

as a buffer on two surfaces of a movable-member, and to allow the passage of a rod through two parts of the hole in its center.

3. The combination of a stationary block, 5 a rod adapted to slide with relation thereto, a shoulder borne by the said block and having a passage therethrough for the said movable-member, an enlargement borne by the said movable-member, and a silencer

acting as a buffer for an end and side of the 10 said enlargement, the said silencer comprising an elongated relatively thin flexible fiber annulus, the said movable-member passing through two parts of the said hole.

In testimony whereof I hereunto affix my 15 signature.

FREDERICK GRINHAM.
